J. B. PRATT,
MODULATOR,
FILED JAN. 12, 1922.

Inventor:
John B. Pratt,
by *Alfred, Davis*
His Attorney

UNITED STATES PATENT OFFICE.

JOHN B. PRATT, OF SCHENECTADY, NEW YORK, ASSIGNOR TO GENERAL ELECTRIC COMPANY, A CORPORATION OF NEW YORK.

MODULATOR.

Application filed January 12, 1922. Serial No. 528,845.

To all whom it may concern:

Be it known that I, JOHN B. PRATT, a citizen of the United States, residing at Schenectady, in the county of Schenectady, State of New York, have invented certain new and useful Improvements in Modulators, of which the following is a specification.

My present invention relates to modulators of high frequency current, and more particularly to modulators of the type commonly known as magnetic amplifiers.

Devices of this general type as used in the past, described for example in U. S. patent to Alexanderson 1,206,643, have ordinarily been constructed with the closed magnetic core made up of thin laminations. They have been constructed either by first assembling the laminations of the core and then winding the coils on this core by threading the conductor through the opening or by first winding the coils and then assembling the laminations making up the core. This latter method requires that the laminations instead of being continuous must be cut in order to permit them to be inserted within the coils.

The object of my invention is to provide an improved method of constructing the magnetic core of such a device which will be simpler than previous methods and result in an improved product. In carrying my invention into effect I first wind the coils which are to surround the closed magnetic core and then form the core by threading a thin ribbon of magnetic material through the coils making enough turns in this ribbon to provide the desired cross sectional area of the core.

The novel features which I believe to be characteristic of my invention are set forth with particularity in the appended claims, my invention itself, however, both as to its organization and method of operation will best be understood by reference to the following description taken in connection with the accompanying drawing in which Fig. 1 shows diagrammatically the application of my invention to a radio telephone transmitting system, and Fig. 2 is a view of the modulator with a portion of the windings broken away.

As indicated in the drawing, my improved modulator comprises a pair of coils 1 and 2 surrounding the two legs 3 and 4,

of a closed magnetic core made up of thin laminations. In constructing this modulator the coils 1 and 2 are first wound upon the spools 5 and 6, and then placed side by side. The core is then formed by threading a thin ribbon of the desired magnetic material continuously through the spools 5 and 6, enough turns of this ribbon being made to furnish the desired cross-section of the magnetic core. This ribbon may be made of electrolytic iron or mild steel, rolled down to a thickness of about 1 mil and enameled, the enamel furnishing the desired insulation between the turns of the ribbon.

Surrounding the coils 1 and 2 is a winding made up of portions 7 and 8 wound in opposite directions. The winding 7, 8 is connected in series with a radiating antenna 9, which is supplied with high frequency current from a source 10 through the usual coupling transformer 11. The source 10 may be of any form desired; a high frequency alternator, an arc generator, or a vacuum tube generator. Modulation of the antenna current is effected by supplying a telephone current by means of a transmitter 12, and a local battery 13 to the windings 1 and 2.

What I claim as new and desire to secure by Letters Patent of the United States, is:

1. The method of constructing a magnetic device for modulating high frequency currents which consists in winding two similar coils, placing the two coils side by side, and forming a continuous magnetic core for the magnetic field which may be produced by currents flowing in said coils by threading a thin ribbon of magnetic material through said coils.

2. The method of constructing a magnetic device for modulating high frequency currents which consists in winding two similar coils, placing the two coils side by side, and forming a continuous magnetic core for the magnetic field which may be produced by currents flowing in said coils by threading a thin ribbon of magnetic material through said coils, and winding a coil around both of said first mentioned coils either before or after the magnetic core is formed.

3. The combination in a modulator of a pair of similar coils side by side, a core for the magnetic field which may be produced

by currents flowing through said coils formed of a continuous thin ribbon of magnetic material threaded through said coils and a winding surrounding both of 5 said coils.

4. The combination in a modulating system of a pair of similar coils side by side, means for supplying a modulating current to said coils, a core for the magnetic field 10 produced by said modulating currents formed of a continuous thin ribbon of magnetic material threaded through said coils, a winding surrounding both of said coils, and means for supplying high frequency 15 currents to said surrounding winding.

5. The combination in a signaling system of a pair of similar coils side by side, means for supplying audio frequency signaling currents to said coils, a core for the magnetic field produced by said signaling currents formed of a continuous thin ribbon of magnetic material threaded through said coils, a winding surrounding both of said coils, a transmitting circuit in which the surrounding winding is included, and means 20 for supplying high frequency currents to said transmitting circuit.

In witness whereof, I have hereunto set my hand this 6th day of January, 1922.

JOHN B. PRATT.
